UNITED STATES PATENT OFFICE.

JOHN E. GRAYBILL, OF YORK, PENNSYLVANIA, ASSIGNOR TO GENERAL ELECTRIC COMPANY,
A CORPORATION OF NEW YORK.

REFILLING-TOOL.

No. 928,044.

Specification of Letters Patent.

Patented July 13, 1909.

Application filed May 18, 1907. Serial No. 374,424.

To all whom it may concern:

Be it known that I, JOHN E. GRAYBILL, a citizen of the United States, residing at York, county of York, State of Pennsylvania, have invented certain new and useful Improvements in Refilling-Tools, of which the following is a specification.

My invention relates to tools used in replacing filaments in incandescent lamps and the object is to provide a tool with which the various operations incident to removing a burned-out filament and to preparing a lamp for the reception of a new one can be very easily and quickly carried out, and more particularly to provide a tool which enables the operator to bring the anchor wire into a suitable position and by one movement of the tool to cut off the tip of the anchor wire and form a hook thereon for the reception of a new filament.

In the usual method of refilling an incandescent lamp, the operator mounts the lamp in a suitable holder in front of him and makes a small opening in the tip of the bulb. Through this opening he removes the burned out filament and uses one tool to scrape the leading-in wires to rid them of the paste used to attach the filaments to them. He then uses another tool to cut off the tip of the anchor wire which is covered with the paste used to fasten the filament to the anchor wire and then with still another tool forms the tip of the anchor wire into a hook to receive the new filament. As the opening through which the tools must be introduced is very small, these various operations are performed with considerable difficulty and when ordinary tools are used it is necessary that the operator be skilled in this particular art before satisfactory results can be obtained, but when a tool embodying my invention is used, the various operations are performed with much greater facility and the operator need not necessarily be skilled in order to secure satisfactory results.

In carrying out my invention I mount any suitable devices for performing various operations upon a support in such a manner that the devices may be introduced through a small opening into the bulb of the lamp which is to be renewed, and arrange these devices so that they are operated in proper sequence by movement of actuating means mounted upon the support and extending to

a point always outside the bulb so that the operator has as complete control of the operation of the devices inside the bulb as he would have if the bulb were absent. The tool may carry suitable devices for performing any of the operations required in renewing a lamp, but the preferred form of device is a combined cutter and hook former for cutting off the paste covered tip of the anchor wire and forming the end of the wire into a hook to hold the new filament; these operations being performed by one movement of the actuating means and without requiring any skill on the part of the operator.

My invention will best be understood in connection with the accompanying drawings which are merely an illustration of one of the many embodiments of my invention and in which—

Figure 1 shows in elevation a re-filling tool constructed in accordance with my invention; Fig. 2 is a longitudinal section of the tool shown in Fig. 1; Fig. 3 is a view of the end of the tool showing the groove by means of which the anchor wire is bent; Fig. 4 a view at right angles to that shown in Fig. 3, showing the cutting edges and the forming die for making the hook in the end of the anchor wire; Fig. 5 a view showing the application of the tool to an incandescent lamp; Fig. 6 a view showing the parts in position to cut off an anchor wire; and Fig. 7 a view of the end of a stem showing the anchor wire after the tip has been cut off and a new hook has been formed.

My invention may be embodied in many different forms, but in the form shown in the drawings the operating members are mounted on a support comprising a handle 95 1 so shaped that it may be easily clasped by the operator, and carrying operating members, one of which may be a tube easily introduced into the bulb of an incandescent lamp through a small opening in the end of 100 the bulb to reach the parts of the lamp, such as the anchor wire, which are to be engaged by the operating members, the other operating member being shown in the drawings as a rod 3 slidably mounted in the tube 2 and 105 normally held in the inoperative position shown in Fig. 2 by means of a spiral spring 4 surrounding the rod engaging a pin passing through it. The operating members are actuated by moving the rod 3 longitudinally 110

in the tube 2 by means of an operating lever 5 pivoted to the handle 1 on a pivot 6. The working parts of the operating members are preferably, though not necessarily, mounted 5 near the end thereof, and in the drawings the end of the tube 2 is preferably formed to facilitate bending the anchor wire to one side to a position where the tip covered with paste can be cut off. Fig. 3 shows the portion 10 on the end of the tube 2 with a guide or groove 8 therein of the proper size and shape to engage the anchor wire for enabling the operator to bend it to the position shown in Fig. 5. This operating member also comprises 15 a cutter 9 to cut the anchor wire, and a forming die 10 to shape a hook on the anchor wire after it is cut. The cutter 9 cuts the wire by coöperating with a cutter 11 carried upon and moved by the other operating member, which is shown as the rod 3. The end of the anchor wire is formed into a hook by the coöperation of the forming die 10 with another forming die consisting of a lug 12 on the end of the rod 3 and of the cutter 25 11, which preferably has its cutting edge so placed that the tip of the anchor wire is cut off before the forming dies begin to act. The several operations on the anchor wire are therefore performed in succession during 30 one stroke of the rod 3, which stroke is uni-directional with relation to the other operating member.

The operation of this device is as follows: A small opening is made in the tip of the 35 bulb and the tool is introduced as shown in Fig. 5. The anchor wire is caught in the groove 8 and bent to one side until it assumes the position shown in Figs. 5 and 6. The tool is then placed so that the anchor wire 40 comes between the cutters 9 and 11, as shown in Fig. 6, and the rod 3 is moved endwise by means of the handle 5. The first result of this movement is to bring the cutters 9 and 11 together, thereby cutting off the tip 45 of the anchor wire covered with the paste which held the burned out filament. Further movement of the operating rod 3 brings the projection 12 into engagement with the anchor wire on one side of the forming 50 die 10, while the side of the cutter 11 engages the cut end of the wire on the side of the forming die 10, the lug 12 and the cutter 11 coöperating to make a forming die to bend the wire around the forming die 10 into the 55 shape of a hook, as shown in Fig. 7. When the hook has been formed, and the dies are gripping the wire, the tool is moved to bend the wire back to the position shown in Fig. 7, and a slight pull upon the wire straightens it. 60 anchor wire from the tool, and the lamp is ready to receive the new filament. If the tool is so manipulated that the wire enters the cutter from the side opposite that shown in Fig. 6, the wire is cut off and no hook is 65 formed, hence the tool may be used to cut

off the paste covered tips of the leading-in wires, which do not require a hook on the end thereof.

My invention may be embodied in many other forms than those shown and described and I, therefore, do not wish to be restricted to the precise form shown but intend to cover by the appended claims all changes and modifications within the spirit and scope of my invention.

What I claim as new and desire to secure by Letters Patent of the United States, is,—

1. A refilling tool for incandescent lamps comprising two elongated members adapted to be inserted in the bulb of the lamp and mounted to move longitudinally of each other, said members being provided with lugs positioned to coöperate and to perform on a wire a plurality of operations in succession during the uni-directional movement of said members longitudinally of each other.

2. A refilling tool for incandescent lamps comprising two elongated members adapted to be inserted in the bulb of the lamp and mounted to slide longitudinally on each other, each member being provided with cutting blades and lugs positioned to coöperate and thereby cut the anchor wire and bend it to form a hook during the longitudinal movement of said members.

3. A wire working tool comprising two elongated members suitable for insertion in the bulb of an incandescent lamp and mounted to slide longitudinally of each other, each member being provided with a cutting blade and a lug arranged with their sides parallel to the direction of movement of said members, the cutting blades being positioned to engage each other and a lug on one member being positioned to pass between the lug and the cutting blade on the other member and thereby bend the wire to form a hook.

4. A wire working tool comprising two elongated members mounted to slide longitudinally on each other, each member being provided with a cutting blade and a lug positioned with their sides parallel to the direction of movement of said members, the lug on the first member being positioned to pass between the lug and cutting blade on the second member and the cutting blade on one of said members extending beyond its adjacent lug to engage the cutting blade on the other member and thereby cut a wire before the lugs engage the wire.

5. A refilling tool for incandescent lamps comprising a tubular member adapted to be introduced into the bulb of a lamp, a cutting blade formed as a longitudinal extension beyond the tubular portion of said member and a rod with a cutting blade on the end thereof slidably mounted in said tubular member to move longitudinally

thereof and thereby bring the cutting blades into engagement.

6. A refilling tool for incandescent lamps comprising a tubular member adapted to be introduced into the bulb of the lamp, a rod mounted in said tube to slide longitudinally thereof and coöperating lugs on said member and said rod positioned to coöperate to cut the anchor wire of the lamp and then

bend the end of the anchor wire to form a 10 hook.

In witness whereof, I have hereunto set my hand this fourteenth day of May, 1907.

JOHN E. GRAYBILL.
